Primary Examiner — Karen E Kearney*Assistant Examiner* — Sharon S Oum(74) *Attorney, Agent, or Firm* — Banner & Witcoff, Ltd.(57) **CLAIM**

The ornamental design for a display screen with icon group and display screen with icon set, as shown and described.

DESCRIPTION

FIG. 1 is a front view of a display screen with icon group showing my new design; and, FIG. 2 is a front view of a display screen with icon set showing my new design.

The broken lines illustrate the display screen and form no part of the claimed design.
